UNITED STATES PATENT OFFICE.

GEORGE E. PARMENTER, OF WALTHAM, MASSACHUSETTS.

DESIGN FOR A PUZZLE-BLOCK.

SPECIFICATION forming part of Design No. 28,047, dated December 14, 1897.

Application filed November 1, 1897. Serial No. 657,115. Term of patent 7 years.

To all whom it may concern:

Be it known that I, GEORGE E. PARMENTER, of Waltham, in the county of Middlesex and State of Massachusetts, have invented and produced a new and original Design for Puzzle-Blocks, of which the following is a specification, reference being had to the accompanying drawings, forming part thereof.

Figure 1 of the drawings represents an obverse view of a puzzle-block illustrating my new design. Fig. 2 represents a reverse view of the same.

The principal features of my new design for puzzle-blocks consist in the series of channels and depressions on the obverse of the block, the series of channels and depressions on the reverse of the block, and the perforations which connect certain of the channels at one side of the block with certain other channels or depressions at the opposite side of the block.

In the drawings on the obverse the depression 5 has the channel 6, with the perforation 7, adjacent to which are the perforations 8 and 9. Above these is the channel 10, with the perforations 11 and 12. To the left is the channel 13, with the perforations 14, 15, and 16, the depression 17, connected by the channel 18 with the perforation 19, the channel 20, with the perforations 21 and 22, the perforation 23, the channel 24, with the perforations 25 and 26, the channel 27, with the perforations 28, 29, and 30, the channel 31, with the perforations 32 and 33, the channel 34, with the perforations 35 and 36, the channel 37, with the perforations 38 and 39 and having the branch channel 40, with the perforation 41, the channel 42, with the perforations 43 and 44, the channel 45, with the perforations 46 and 47, the channel 48, with the perforations 49 and 50, the channel 51, with the perforations 52 and 53, the depression 54,

with its channel 55 and the perforation 56, the channel 57, with the perforations 58 and 59, the depression 60, with its perforation 61, 45 and the depression 62, with its channel 63 and perforation 64.

On the reverse the perforations 7 and 8 connect with the channel A, from which the channel B extends to the depression C and 50 the channel D to the perforation 12. The depression E embraces the perforation 16. The channel F connects the perforations 26 and 30. The channel G connects the perforations 9, 13, and 36. The channel H connects 55 the perforations 10 and 15. The channel I extends along the edge portion of the block, connecting the perforations 35 and 38, having the branch J, with the depression K, the branch L, which connects with the perforation 55, and the branch i, connecting with the channel M, at the ends of which are the perforations 19 and 41. The channel N connects the perforations 32 and 39. The channel O connects the perforations 21 and 43. 65 The channel P connects the perforations 22 and 25 with the depression p. The L-shaped channel R connects the perforations 23, 33, and 28. The depression S embraces the perforation 29. The channel T connects the 70 perforations 44 and 49. The channel U connects the perforations 46 and 50. The channel V connects the perforations 47 and 52. The channel W connects the perforations 58 and 64, and the L-shaped channel x connects 75 the perforations 53, 59, and 61.

What I claim is—

The design for puzzle-block herein shown and described.

GEORGE E. PARMENTER.
